UNITED STATES PATENT OFFICE.

WILLIAM C. OSTRANDER, OF PITTSFIELD, MASSACHUSETTS, ASSIGNOR TO HAMPDEN
GLAZED PAPER & CARD COMPANY, OF HOLYOKE, MASSACHUSETTS, A CORPORA-TION OF MASSACHUSETTS.

DESIGN FOR COVER PAPER OR THE LIKE.

Application filed March 16, 1926. Serial No. 16,931. Term of patent 14 years.

To all whom it may concern:

Be it known that I, WILLIAM C. OSTRANDER, a citizen of the United States residing at Pittsfield, in the county of Berkshire and State of Massachusetts, have invented a new, original, and ornamental Design for Cover Paper or the like, of which the following is a specification, reference being had to the accompanying drawing, forming a part thereof.

The figure is a view of a piece of cover paper or the like embodying my new and original ornamental design.

I claim the ornamental design for cover paper or the like as shown.

WILLIAM C. OSTRANDER.
